(57) **CLAIM**

The ornamental design for an ice ball press, as shown and described.

DESCRIPTION

FIG. 1 is a perspective view of an ice ball press, showing the new design;

FIG. 2 is a front elevation view thereof, the rear elevation view being identical;

FIG. 3 is a right side elevation view thereof, the left side elevation view being identical;

FIG. 4 is a top plan view thereof;

FIG. 5 is a bottom plan view thereof;

FIG. 6 is a perspective view of a bottom portion of the ice ball press with a top portion removed;

FIG. 7 is a front elevation view of the bottom portion of the ice ball press with the top portion removed, the rear elevation view being identical;

FIG. 8 is a right side elevation view of the bottom portion of the ice ball press with the top portion removed, the left side elevation view being identical;

FIG. 9 is a top plan view of the bottom portion of the ice ball press with the top portion removed; and,

FIG. 10 is a perspective view of the top portion of the ice ball press.

The broken lines show portions of the ice ball press that form no part of the claimed design.

1 Claim, 7 Drawing Sheets
